DESIGN FOR A LATHE TOOL

Henry M. Beyreis, United States Army

Application January 22, 1942, Serial No. 105,366

Term of patent 3½ years

To all whom it may concern:

Be it known that I, Technical Sergeant Henry M. Beyreis, United States Army, a citizen of the United States, residing at Fort Cook, Nebraska, have invented a new, original, and ornamental Design for a Lathe Tool, of which the following is a specification, reference being had to the accompanying drawing, forming part thereof.

Fig. 1 is a side elevational view of a lathe tool, showing my new design,

Fig. 2 is a plan view thereof,
Fig. 3 is an end elevational view, and
Fig. 4 is an elevational view of the opposite end.

I claim:
The ornamental design for a lathe tool, as shown.

HENRY M. BEYREIS.
